LOCK CONSTRUCTION

Sigurd Brantingson, Palisades Park, N. J., assignor to Francis Keil & Son, Inc., a corporation of New York

Application May 5, 1939, Serial No. 271,818

8 Claims. (Cl. 70—378)

This invention relates to lock construction, more particularly of the pin tumbler type.

One of the objects of this invention is to provide a pin tumbler type of lock that has a certain type of structural characteristics for resisting picking, with means to facilitate key insertion and removal. Another object is to provide a lock construction of the above-mentioned character that is difficult, if not impossible, to pick, and that will reliably interfere with and make more complicated and difficult certain of the usual or normal steps employed in attempting to pick the lock. Another object is to provide a lock construction of the above-mentioned type that will be inexpensive to manufacture, both as to its individual parts and as to assembly thereof. Another object is to provide a dependable pick-resisting lock construction free from such complications as make manufacture, assembly, repair, replacement, and the like, cumbersome or expensive. Another object is in general to improve the construction and operation of pin tumbler types of locks. Other objects will be in part obvious or in part pointed out hereinafter.

25 The invention accordingly consists in the features of construction, combinations of elements, and arrangements of parts as will be exemplified in the structure to be hereinafter described and the scope of the application of which will be indicated in the following claims.

In the accompanying drawing in which is shown by way of illustration one of the various possible mechanical embodiments of the various features of my invention,

35 Figure 1 is a central vertical longitudinal sectional view through the lock construction;

Figure 2 is a detached view on an enlarged scale and partly in central vertical section, of a preferred form of tumbler pin construction, and

40 Figure 3 is a duplication of a portion of the construction shown in Figure 1 but on a larger scale.

Similar reference characters refer to similar parts throughout the several views in the drawing.

45 Referring first to Figure 1, I have there shown a lock casing generally indicated by the reference character 5 of any suitable shape to receive and coact with a suitably shaped key plug generally indicated by the reference character 6. Preferably the casing 5 has a lower casing portion 7 generally cylindrical in shape and bored out, preferably also cylindrically, as at 8, to movably, preferably rotatably, receive the key plug 6 which accordingly is preferably cylindrical in

shape to fit suitably into the bore 8 for movement relative thereto.

In the illustrative construction, the key plug 6 is to partake of rotary movement relative to the bore 8 of the casing 5 and hence any suitable means may be employed to restrict or limit relative movement in an axial direction; such means may comprise a flange 9 at the front end of the key plug 6, received in a suitable counterbore 10, while at the other end of the key plug 6 the latter 10 preferably extends beyond the end of the casing or bore to receive any suitable means, such as a member 11 to limit or restrict movement of the key plug toward the right, as viewed in Figure 1. The member 11 may take any suitable form, such as a ring-like member suitably secured to the key plug and coacting with or engaging the end portion of the casing.

The key plug and casing are provided with suitable bores or recesses, preferably cylindrical, for the reception of tumbler pins, and for that purpose the casing 5 may have an upward extension 12 in which are formed, as by drilling, a suitable number of cylindrical bores or recesses whose axes intersect the axis of the bore 8 and hence 25 of the key plug 6 and, illustratively, I may provide five such recesses, as at 13, 14, 15, 16 and 17. The key plug 6 is provided with similar bores 18, 19, 20, 21 and 22; the latter, in one position of the key plug 6 relative to the bore 8, are respectively 30 aligned with the above-mentioned casing recesses, the respective upper and lower recesses, when so aligned, having their junctions coincident with the junction between the key plug and the bore 8. For simplicity and inexpensiveness of manufacture, these bores are preferably all of the same 35 diameter. The key plug 6 is provided with any suitable form of key slot generally indicated at 23 and cross-sectioned in any suitable way as by longitudinally extending ribs 24, if desired, it being noted that the tumbler recesses in the key plug intersect and extend downwardly into the key slot 23 so that the tumbler pins received in the former are exposed to the appropriately shaped edge of the proper key inserted into the 45 key slot.

In so far as certain features of my invention are concerned, it might be noted that it has heretofore been proposed to employ, for the tumbler pins to be received in the tumbler recesses of the 50 casing portion 12, a construction like that shown in Figure 2, according to which each tumbler pin is made up of a shank 26 on which are strung a suitable number of washers or apertured disks 27, suitable end disks 28, 29 holding them assembled 55

to the shank 26 so as to prevent substantial movement thereof along the shank 26 while permitting free sidewise or lateral play of, or relative displacement between, the members 27 to an extent 5 permitted by the difference between the diameter of their central apertures and the diameter of the shank 26.

The end members 28, 29 may be secured in any suitable way; thus, member 29 might be integral 10 with the shank 26, while the other end member 28 may be held in place as by suitably heading over the end of the shank 26, as at 30.

Prior proposals to employ tumbler pins of this character do not result in satisfactory operation 15 of the lock; when all of the casing tumbler pins are of this construction, the normal locked position of the key plug relative to the casing finds all of the upper tumbler pins of this type bridged across the junction between key plug and casing 20 bore and it is possible in such a construction, made according to prior proposals, to effect such a jamming of the parts that it is impossible to insert even the intended key to effect authorized 25 actuation of the lock. For example, some lateral play between the washer-like members 27 (Figure 2) must be present if resistance to picking is to be retained but with all of the tumbler pins bridging the above-mentioned junction, that same lateral play is present so that it is possible, unintentionally, to bring about or leave the construction 30 in a locked position but with the tumbler recesses in the key plug displaced from or not aligned with the tumbler recesses in the casing, due to such permissible side or lateral play. If, 35 then, the proper key is inserted, a jamming occurs just as it is intended to take place when attempt is made to pick the lock; the misalignment of the upper and lower tumbler recesses thus insures the presence of a ledge against which 40 the washer-like parts 27 can catch to resist upward movement of the tumbler pins, and only one disk member of one tumbler pin need catch to block the insertion of even the proper key. In so far as certain features of this invention are 45 concerned, a dominant aim is to overcome such deficiencies and to make it possible in a dependable and inexpensive way to utilize the advantages of the just-described type of construction without incurring the liability of facing its 50 disadvantages.

In Figure 1 is shown a preferred or illustrative construction whereby I am enabled to overcome the above-mentioned deficiencies. Thus, in plug tumbler recesses 19, 20, 21 and 22, I provide tumbler pins 32 which may be straight cylindrical pins and of varying lengths, according to 55 the coding of the key, to bring their upper ends, when their lower ends bottom in the tumbler recesses, below the junction between key plug and casing bore. In the casing tumbler recesses 14, 60 15, 16, 17, I provide tumbler pins 33 of the type above described and shown in Figure 2; they may be and preferably are of the same length, thus to facilitate uniformity of production, and they 65 are pressed downwardly by springs 34, the tumbler recesses being closed at their upper ends in any suitable way as by a closure plate 35.

The tumbler pins 32, 33 of each pair are preferably of the same outside diameter and hence 70 preferably have the same fit relative to their bores or recesses; this fit is preferably somewhat loose and might be typified by giving the tumbler pins 32, 33 an outside diameter of say 0.115 inch where the bores or recesses in which they operate are a diameter of 0.123 inch. Such a difference

in these diameters includes also a factor adequate to compensate for possible end play, that is, play in an axial direction of the key plug 6 relative to the casing bore 8.

In plug tumbler recess 18 I position a tumbler 5 pin 37 which is of a length such that when it bottoms in its recess 18 or is otherwise in its lowermost or normal position, its upper end is flush with the junction between key plug and casing bore, as is better shown in the enlarged view 10 of Figure 3, and it preferably fits relatively snugly in its bore 18, being illustratively of a diameter of 0.118 inch, the difference taking into account the above-mentioned end play.

Coacting with tumbler pin 37 and inserted into 15 the casing tumbler recess 13 is a tumbler pin 38 which, like the tumbler pin 37, is cylindrical and preferably has the same relatively snug fit with its bore or recess 13, being hence of a diameter of 0.118 inch, the tumbler recesses 18 and 13 being 20 of a diameter of 0.123 inch and hence, as earlier noted, of the same diameter as the rest of the tumbler pin recesses.

The adjacent ends, however, of the tumbler 25 pins 37 and 38 I preferably shape so that the two pins coact to tend to maintain themselves in coaxial alinement, a spring 39 of sufficient stiffness in the casing tumbler recess 13 acting upon the upper tumbler to press it toward and in engagement with the lower tumbler. 30

In Figure 3 is shown an illustrative and preferred form of shaping of the adjacent end portions of pins 37 and 38. Thus, the upper end of pin 37 has a recess 40, formed as by drilling or counterboring, and it provides, exposed upwardly, a surface which is shaped substantially like that of an inverted cone whose axis is coincident with the axis of the pin 37. The lower end of the upper pin 38 is rounded off as at 41, the surface being a surface of revolution whose axis is coincident with the axis of pin 38 and is of such curvature that it enters to a substantial extent into the conical recess 40, the curvature of its upper side portions, as seen in Figure 3, being preferably relatively slight and approximating, 45 for example, the surface of a frustum of a cone. 40

When pressed together, the end portion 41 enters the recess 40 and becomes peripherally tangent thereto, thus alining the two pins to bring their axes into coincidence and also bringing their 50 respectively closely fitting tumbler pin recesses 13 and 18 into coaxial alinement, the coaction between the spring 39 and the surfaces of the parts 41 and 40 normally maintaining these relationships, thus also maintaining the respective 55 upper and lower tumbler recesses of the tumbler pins 33-32 likewise in coaxial alinement.

In achieving these relationships, the coacting surfaces of the parts 41 and 40 act as cam-like force-multiplying parts to translate the comparatively small force of the spring 39 into a relatively large side thrust to impose upon the movable key plug 6 the thrust or force necessary to shift it, in the illustrative embodiment by a rotary movement, sufficiently to bring the key plug tumbler 65 recesses into alinement with the casing tumbler recesses.

The key for operating the lock, where the pin 37 is dimensioned as to length, as in the illustrative embodiment, so that its upper end is 70 flush with the junction between key plug and casing bore, has a notch, for pin 37, of such depth that when the key is completely inserted pin 37 again bottoms in its recess 18. During insertion of the key, the other portions of the key raise 75

the pin 37 to bring its upper end into the tumbler recess 13 and thus pin 37, in bridging the junction of tumbler recesses 18 and 13, holds the key plug in proper position to maintain registry 5 of the other upper and lower recesses so that the other portions of the key may freely position the other tumbler pins 32—33 without the washer-like parts of the latter becoming jammed at the junction.

10 The key may now be freely turned to move the key plug 6, as in a locking or unlocking movement. At the beginning of this movement, rotary in the illustration, the surface of the recess 40 in coaction with the surface of the portion 15 41 of the upper pin 38, simply cams the latter upwardly, part 41 being cammed over the upper peripheral edge of the recess 40 of the lower pin 37.

At the conclusion of the movement necessary 20 to thereafter effect withdrawal of the key, the rounded end portion 41 of the upper pin 38 slides over the peripheral end or edge portion of the lower pin 37 and under the action of spring 39 is cammed or forced downwardly into the recess 25 40, in effect snapping the two pins 37 and 38 and hence the key plug and casing tumbler recesses into axial alinement, also taking up any end play, and holding that alinement of parts, whence the key may be promptly withdrawn. 30 again without danger of having any of the displaceable washer-like parts 27 of the tumbler pins 33 jam or catch at the junction between the now alined plug tumbler recesses and casing tumbler recesses. After removal of the key, the 35 continued coaction between tumbler pins 37 and 38 continues to maintain the desired alinement of the parts so that subsequent insertion of the key takes place easily and smoothly.

But by reason of such coactions, I also achieve 40 greater security against picking of the lock whether or not the tumbler pins 33 are of the type above described and shown in Figure 2. With the tumbler pin 37 dimensioned as above described in the illustrative embodiment, it has to bottom in its recess 18 if relative movement 45 between key plug and casing is to take place, for any upward movement projects it across the junction between key plug and casing bore and blocks such relative movement; that action could 50 take place if pin 37 is raised as by a picking implement inserted into the key slot and usually accompanies any attempt to lift one of the pins 32 to the rear of pin 37, since in such case attempt has to be made to by-pass the pin 37 without raising it.

55 Assuming that such attempt is successful, the succeeding attempts to raise the rear pins to catch the upper pins on a ledge caused by displacing the key plug relative to the casing, must be accompanied by exerting a delicate force upon the key plug 6, usually a torsional force, to bring about a displacement sufficient to create such a ledge; this is usually done by cut and try methods in which sensitiveness of control of the displacing or torsional force exerted upon the key 60 plug is practically vital. But any such attempts to displace the key plug, according to my invention, are met by the greatly multiplied force of the spring 39 acting, through the wedge-like or 65 cam faces of the parts 40, 41, in opposition to such displacing or torsional force. This force of opposition is, due to the relative shaping of the parts 40 and 41, greatly in excess of the comparatively small force exerted by the spring 39 and, again by appropriately shaping the parts 70

40, 41, may have a variable, as distinguished from straight-line, effect or relationship to the amount of misalignment between the axes of the pins 37 and 38.

Thus, the individual who attempts to pick the lock meets with a substantial force of opposition to his control of the displacement of the key plug, thus upsetting the necessary sensitiveness of control of the manually applied displacing force, and where, as in the preferred case, 10 the cam or wedge effect in multiplying the force of the spring 39 is variable and is hence a non-linear function of the displacement of the axes of the pins 37 and 38, this opposing force partakes of such variation or change that the sensitiveness of displacement or torsional control, 15 manually, of the key plug relative to the casing, in the effort to catch the rear tumbler pins at the right elevation, is completely upset and picking of the lock made so time-consuming or 20 so difficult or impossible that, for practical purposes, frustration of picking attempts results.

As earlier above indicated, the tumbler pin 37 is preferably of such a length that, when it assumes its normal or lowermost position, its upper 25 peripheral edge portions are substantially at or in the junction between the key plug 6 and the bore 8. In the illustrative embodiment, that preferred relationship is achieved by letting the tumbler pin 37 bottom in its bore 18; the bore 30 18 may be given any suitable depth or axial length and, for example, it may be of the same length as the bores 19, 20, 21, 22, though, as in Figure 1, it may be desirable to give the bore 18 a greater depth, somewhat as indicated, particularly where it may be desired to relate the lower 35 end of the tumbler pin 37 to one of the longitudinally extending ribs 24 in the key slot 23.

Thus, it will be seen that there has been provided in this invention a lock construction in 40 which the various objects above noted, together with many thoroughly practical advantages, are successfully achieved. It will be seen that the construction is of a thoroughly practical nature, is capable of inexpensive manufacture, and is 45 well adapted to meet the conditions of hard practical use.

As many possible embodiments may be made of the above invention and as many changes might be made in the embodiment above set forth, it is to be understood that all matter hereinbefore set forth or shown in the accompanying drawing is to be interpreted as illustrative and not in a limiting sense.

I claim:

1. A lock construction comprising a casing having a bore, a key plug movably mounted in said bore, said key plug having a key slot and a plurality of tumbler bores intersecting said key slot, said casing having a plurality of tumbler bores respectively alignable with said first-mentioned tumbler bores, tumbler pins in said key plug tumbler bores, spring pressed tumbler pins in said casing tumbler bores, at least one of said tumblers in said casing bores comprising a member having strung thereon a plurality of washer-like parts capable of relative lateral displacement to present one or more projecting edges capable of catching upon the ledge formed between said key plug and casing upon inappropriate alignment of the key plug bore and casing bore in which said tumbler pin is slidable, at least one of the remaining tumbler pins in a casing bore and its coacting key plug tumbler pin having a relatively close fit with their bores and having 70 75 80 85 90 95 100

their adjacent ends provided with interfitting means capable, in response to the spring pressure exerted on the casing tumbler pin, of bringing said two pins into coaxial alinement and thereby forcing such displacement of the key plug relative to the casing that the respective tumbler bores of the latter are brought into coaxial alinement, thereby preventing a laterally displaced part of said first-mentioned tumbler pin from catching and jamming the insertion or removal of the key relative to said key slot.

5 10 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

in said casing tumbler bores, and means for upsetting sensitiveness of control of manual application to the key plug of a force for displacing the key plug relative to the casing such as is necessary in the attempt to pick the lock construction, said last-mentioned means comprising means acting upon said tumbler pin in response to the pressure exerted thereon by its companion casing tumbler pin for exerting a displacing force upon the key plug, through the key plug tumbler pin, and thereby to interfere with the said force of displacement manually applied as aforesaid.
